UNITED STATES PATENT OFFICE.

FRED C. BOYD AND CHARLES F. LITTLEJOHN, OF NEW HAVEN, CONNECTICUT, ASSIGNEES TO THE FARADAY CO., OF NEW HAVEN, CONNECTICUT, A CORPORATION.

HYDROCARBON-BURNER.

1,294,028.

Specification of Letters Patent. Patented Feb. 11, 1919.

Application filed October 22, 1918. Serial No. 259,223.

To all whom it may concern:

Be it known that we, FRED C. BOYD and CHARLES F. LITTLEJOHN, citizens of the United States, residing at New Haven, in the county of New Haven and State of Connecticut, have invented a new and useful Improvement in Hydrocarbon-Burners; and we do hereby declare the following, when taken in connection with the accompanying drawings and the characters of reference marked thereon, to be a full, clear, and exact description of the same, and which said drawings constitute part of this application, and represent, in—

Fig. 1 a top or plan view of a hydrocarbon burner constructed in accordance with our invention.

Fig. 2 a side view of the same.

Fig. 3 a vertical sectional view of one of the burners.

Fig. 4 a sectional view on the line 4—4 of Fig. 1.

Fig. 5 a broken perspective view illustrating the location of our improved burner in a cook stove.

This invention relates to an improvement in hydrocarbon burners particularly adapted for use in burning kerosene oil, the object of the invention being to provide a burner which may be inserted into the ordinary fire-box of a cook stove or range, heating stove, furnace or other device in which coal or wood is commonly used; and the invention consists in the construction hereinafter described and particularly recited in the claims.

In carrying out our invention we employ a base-plate 6 preferably of cast metal and corresponding in dimensions to the number of burners used. In illustrating our invention we have shown a device comprising two burners. This base-plate is supported upon an open rectangular casing 7 provided at its lower edge with an outwardly projecting flange 8 adapted to rest upon the grate in the usual fire-box and so as to support the base-plate above the grate and provide a passage for air drawn upward through the grate. The base-plate is formed around its edge with an upwardly projecting flange 9 and with burner openings 10, the openings being surrounded by collars 11. The base-plate is also formed with tubular openings 12 through which feed pipes 13 extend, these pipes leading

through the ordinary dampers 14 in the front of the stove to a tank 15. Resting on the base around the edge of the collars 11 is a housing 16 forming a mixing chamber above and around the collars. These 60 housings are formed at their lower edge with lugs 17 by which the housing may be secured to the base-plate 6 by screws 18. The lower edges of these housings are formed with notches 19 to permit air to 65 be drawn into the mixing chamber. These housings are formed at their upper ends with chimneys 20 smaller in diameter than the diameter of the housing so as to form annular priming channels 21 for the purpose as will hereinafter appear. The feed-pipe 13 extends upward over the mixing chamber and is formed with a coil which extends down through the mixing chamber and terminates in an upwardly extending 70 burner tube 22 provided at its upper end with a burner nipple 23. Over the coil in each mixing chamber is a distributor 24 which is suspended on an arm 25 mounted in a post 26 which is secured to the base- 75 plate 6 between the burners. The device is placed in the firebox of an ordinary cook stove as indicated in Fig. 5 of the drawings upon the grate-bars therein, or it may be placed in any furnace or other fire-box 80 where required. Upon the flange 8 may be placed any packing, such as ashes, so as to cut off any upward draft through the grate which will all be deflected upward through the casing 7. The pipe from the fuel supply is then opened to permit the fuel to flow to the burner and one or more of the burners may be used as is required. The heat from the burner vaporizes the fluid in the feed tube as it passes to the burner 85 tip so that it emerges in the form of gas, and this gas is spread by the deflector so as to cover the heating surface of a range or furnace. In first starting the burner, it may be desirable to place some kerosene or 90 other burning fluid in the priming channel 21 so as to heat the burning fluid as it first comes to the burner tip. This inwardly set priming channel also restricts the upper end of the mixing chamber so 95 that air entering that chamber will be mixed with the gas discharged through the burner tip and thus facilitate combustion. The hot air in the fire-box will be drawn into the mixing chamber through the open- 100

110

ings 19 so as to further assist in combustion and preferably, and as shown, the upper inner edge of the chimney or priming cup will be formed with notches 27 through 5 which flames will be directed to the upper part of the coil. It will thus be seen that a burner for liquid fuel, such as kerosene, is provided, which is readily adapted to be placed in any fire-box without requiring any change in the structure of the apparatus into which it is placed.

We claim:—

1. A hydro-carbon burner comprising a plate formed with an opening, a mixing 15 chamber around said opening, said mixing chamber formed at its upper end with a priming cup, a feed pipe extending over said chamber and downward through the chamber in the coil, said pipe terminating 20 in a centrally arranged burner tip.
2. A hydro-carbon burner comprising a plate formed with an opening, an upwardly projecting collar around said opening, a mixing chamber casing mounted on the 25 plate around said collar, said mixing chamber casing formed in its lower edge with notches and at its upper end with a priming cup, a coil within said mixing chamber.

ber leading to the source of supply, and a burner connected with the lower end of 30 the coil.

3. A hydro-carbon burner comprising a base-plate formed with an opening, an upwardly projecting collar around said opening, an open casing upon which the said 35 base is supported, said base also formed around its outer edge with an upwardly projecting flange, a mixing chamber casing secured to said base around said collar, said mixing chamber casing formed in its 40 lower edge with notches, and at its upper edge with an inset annular priming cup, a coil in said mixing chamber, said coil connected with the source of supply, a burner connected with the lower end of said coil, 45 and a distributor plate mounted above the coil.

In testimony whereof, we have signed this specification in the presence of two subscribing witnesses.

FRED C. BOYD.
CHARLES F. LITTLEJOHN.
